UNITED STATES PATENT OFFICE.

GEORGE ALBERT LYON, OF PHILADELPHIA, PENNSYLVANIA.

AUTOMOBILE-BUFFER.

1,325,743.

Specification of Letters Patent. Patented Dec. 23, 1919.

Application filed July 15, 1919. Serial No. 310,937.

To all whom it may concern:

Be it known that I, GEORGE ALBERT LYON, a citizen of the United States, and resident of Philadelphia, county of Philadelphia, State of Pennsylvania, have made a certain new and useful Invention Relating to Automobile-Buffers, of which the following is a specification, taken in connection with the accompanying drawing.

10 The invention of this application, which is a continuation in part of my co-pending application No. 311,906, renewed July 18, 1919, that is, contains subject-matter taken therefrom, relates to automobile buffers 15 formed of or comprising resilient strips of steel or other metal and in which the strips or at least the connector portions thereof are given a curved or otherwise bent or non-planiform cross-section so as to promote the alining action of the connector portions of such coöperating strips when bolted, clamped or otherwise forced together in assembling the buffer. Additional alining action may be secured by forming 25 at least one of such connector portions with an alining flange adapted to coöperate with the other connector portion of the coöperating buffer member and these flanged or bent sections naturally increase the stiffness and 30 resilient strength of the buffer members which is desirable from some standpoints.

In the accompanying drawing, which shows in a somewhat diagrammatic way 35 illustrative embodiments of the invention,

Figure 1 is a plan view of a buffer and connected supporting devices secured to a Ford automobile.

Fig. 2 is a view thereof taken substantially along the line 2—2 of Fig. 1.

40 Fig. 3 is an enlarged transverse section taken along the line 3—3 of Fig. 2 showing one type of coöperating connector portions which may be used.

Fig. 4 is a plan view of another form of 45 automobile buffer.

Fig. 5 is an enlarged transverse section thereof taken along the line 5—5 of Fig. 4.

Figs. 6 to 9 are corresponding transverse 50 sections showing other forms of resilient strip buffer members or connector portions thereof which may be used.

Fig. 10 is a plan view of another form of automobile buffer; and

Fig. 11 is an enlarged transverse section 55 taken along the line 11—11 of Fig. 10.

The resilient front portion of the buffer

shown in Fig. 1 may consist of two resilient or spring steel strips 1 and 2 extending transversely across the front of the automobile as shown in Fig. 4, the central portions of these strips overlapping one another and being held in position by any suitable clips 3, each strip or bar being then turned back on itself so as to form an end loop 4 which is preferably bent slightly 60 rearward and joined by a curved portion 5 to a connector portion which is adapted to be bolted or otherwise connected to the relatively rigid extension or attaching members 6 of the buffer. This attaching member 65 which is preferably of stiffened flanged construction may be bolted or otherwise connected to the front of one of the side frames 7 of the automobile.

This may be effected by using the arm 9 75 of the headlight or lamp 8 secured to each of the side frames of the ordinary Ford automobile and usually extending from a bracket 10 which engages the outer side of the car frame 7 and extends beneath the 80 lower flange thereof to which it may be secured by a nut 11. The relatively rigid attaching member of the buffer may comprise three parts 12, 13, 14, the forward and rear portions 13 and 14 being preferably of 85 flanged or right angled cross-section, comprising a vertical flange 18 and a top flange 68 as shown in Fig. 3, and the intermediate portion 12 being, if desired, a horizontal plate or portion which connects the forward 90 and rear ends of this member and may rest upon the lamp arm 9 and its bracket 10. These parts may be held in firm and rigid contact by means of a yoke or securing U-bolt 15 whose lower looped portion may 95 extend beneath the horizontal part of the bracket 10 and engage the securing bolt 11 thereof and the upwardly projecting ends of this securing bolt may pass through openings in the plate 12 and be threaded for 100 engagement by nuts which bear upon the top of the plate 12 as shown in Figs. 1 and 2. The rear end of this attaching member may be bent downward beneath the bottom flange of the side frame 7 of the automobile 105 so that this portion 28 may be bolted in position by the bolt 16, a laterally projecting flange 17 being formed on this securing or anchoring nut, if desired.

The vertical flange of the forward portion 13 of this attaching member of the buffer may be of curved or concavo-convex cross-

- section at its front end as shown at 18 in Fig. 3 and the coöperating connector portion of the buffer front member may be of similar shape and firmly bolted or riveted 5 to the flange 18 as shown in Fig. 3. The curved or concavo-convex cross-section of the resilient bars or strips 1, 2 may continue throughout the entire length of the same and serves to stiffen these parts of the buffer and enable it to better resist bending strains as compared to a flat bar, the spring yielding action of the buffer taking place largely in the end loops 4 and curved portions 5.
- 10 15 In the form of buffer shown in Fig. 4 the impact receiving portion which may be formed of one or more resilient or spring steel strips may, if desired, be given a forwardly bowed or arched outline of substantially uniform curvature. As indicated 20 this impact receiving member may comprise the spring steel strips 24 having the connector portions 29, 30, which may overlap and reinforce each other throughout a considerable extent of the buffer front and 25 may be adjustably connected by suitable clips or clamping members, such as 38, which may tightly clamp the ends 45, 46 of these front strips in position when the 30 bolts 31 are tightened to draw the ends 32 of each of these clips together. These impact receiving members may be conveniently 35 made of spring steel strip which has been originally rolled or otherwise formed so as to have a curved or bent cross-section as indicated in Fig. 5 so that a considerable alining action is secured between the coöperating connector portions of such strips because of the curved, bent or non-planiform 40 cross-section given thereto. It is of course understood that this form of reinforced buffer front or impact receiving member may be adjusted so as to have any desired width by clamping or securing the overlapping 45 spring strips 29, 30 in desired position. In this way the integral end loops 4 which may be formed in these spring strips may extend out to the desired extent beyond the wheels of the automobile or other vehicle.
- 50 The ends of these spring strips or members may be turned inward substantially parallel to the adjacent forward portion of the corresponding strip so as to form the in-turned ends 43 to which separate attaching 55 members which are preferably also of resilient or tempered spring steel strip may be adjustably or otherwise connected. Attaching members 65 of this character may in some cases be advantageously formed of 60 spring steel strip which has been rolled to give it a suitably curved or bent alining cross-section so that the connector portions of these coöperating buffer strips fit together so as to be rigidly held in vertical alinement 65 when they are bolted or clamped at

one or more points as by such a clip or clamping device as is shown in Fig. 5. A single clip 38 of this character is often sufficient to insure the desired positioning and secure connection between two such bent 70 cross-section connector portions 42, 43, since even when forced together at a single point these non-planiform strips have a decided self-alining tendency which prevents their slipping or moving out of vertical alinement. If desired, the securing ends 44 of these attaching members may be flattened so as to coöperate to better advantage with the vehicle frames against which they may be clamped or bolted in any desired way. 80 Fig. 6 shows a generally similar form of bent section connector portions of coöperating buffer members which may be used in this general way as the connector portions of the Fig. 4 buffer, or, indeed, the connector portions of the Fig. 1 buffer may be given this form, if desired. In this case the flanged connector portion 18^a of the attaching member which may have an integral flange 68^a may be formed with a concave 90 face against which the convex face of the resilient front strip 2^a of the buffer member may be secured as by the bolt 21. Fig. 7 shows another form of coöperating curved or bent cross-section connector portions 95 which may advantageously be used on coöperating buffer members. In this case, while the resilient strip connector portions are curved throughout, their central portions are somewhat flatter or less curved as 100 compared to the greater curvature of the inclined alining edge portions 47 of these two members 48, 50. When, for example, two such connector portions are bolted together by a bolt 51 their alining angular 105 edge portions are forced into engagement and since they have substantially the same inclination they exert a considerable alining action which is of course increased in proportion to the force with which the two 110 strips are brought together at their central portions 49. This form of self-alining angular edge spring strips may be advantageously used, for example, in the Fig. 4 buffer, and of course the connector portions 115 may obviously be clamped together instead of bolted, if desired.

Fig. 8 shows another form of bent sectioned buffer connector portions which may be used in which the central parts or portions of these strips may be practically or substantially flat as at 55, while the alining edge portions 54 are bent or inclined backward at substantially the same angle in these two coöperating connector members or 125 portions 52, 53. When such coöperating buffer members are bolted or clamped together their edge flanges or alining portions are forced into engagement so as to exert a mutually alining action on each other, while 130

if the strips are of substantially equal thickness throughout, a space is left between the adjacent flat central portions of the strips which localizes the engagement between them at their edge portions. Fig. 9 shows still another form of bent cross-section connector portions which may be used at the buffer front or at the connection between the attaching member and the buffer. In this case the strips 57, 58, which may advantageously be formed of resilient spring steel which may be hardened and tempered, may have inclined or bent alining faces or portions 56 forming an angle of about 90° or so and exerting a powerful mutually alining action when the two strips are clamped or bolted together, as for instance, by the bolt 51^a which may advantageously be formed with a special head to accommodate or fit around the convex face of the outer or forward strip. The angular or V-shaped washer 66 may advantageously be arranged beneath the nut and may fit within the angular recess of the strip 58 so as to have more desirable tightening action. This form of bent self-alining buffer connector portions which may correspond to a pre-rolled spring steel strip forming the front or other portion of the automobile buffer may be used in any of the forms of the buffer illustrated herein as is the case with the other bent or curved section connector portions described.

Fig. 10 shows still another form of automobile buffer which may in this case comprise a single buffer front or impact receiving member 59 which may be of forwardly bowed or arched outline so that the central portion 62 projects beyond the end portions thereof. As indicated in section in Fig. 11 this front strip 59 may be of bent or angular cross-section, the two angular faces 61 being arranged at a relatively large or flat angle to each other and making an angle of about 120° or 130° or so as not to have such a sharp angular appearance as in the Fig. 9 construction and thus give a smoother and somewhat more pleasing appearance, for which purpose the ends of this buffer front may also be curved back or reduced as indicated. The attaching members 60 may, if desired, be formed of similarly bent spring steel strip and may have an outwardly curved portion 61 gradually merging into the curvature of the adjacent portion of the buffer front member so that the ends 63 of these attaching members have substantially the same horizontal curvature as the inner portion of the buffer front and as indicated in Fig. 11 the cross-sections of these connector portions correspond so as to effect a desirable alining action when these connector portions are bolted or clamped together in any suitable way. In this instance a clip or damping device 38 of the general type

shown in Fig. 5 is shown as slipped over these connector portions to tightly force them together and the distance apart of the preferably flattened securing ends 64 of the attaching members may be adjusted in this way, if desired.

This invention has been described in connection with a number of embodiments, forms, proportions, parts, arrangements, materials, methods of manufacture, connection and use, to the details of which disclosure the invention is not of course to be limited, since what is claimed as new and what is desired to be secured by Letters Patent is set forth in the appended claims.

I claim—

1. The automobile buffer comprising a resilient buffer front formed of two spring steel strips having relatively adjustable co-operating connector portions and each having an integral resilient end loop formed with an inturned attacher connector portion, co-operating spring strip attacher members having connector portions adapted to co-operate with the corresponding connector portions of the buffer front, and connecting devices adjustably securing together said co-operating connector portions, some of said connector portions having a stiffening bent alining cross section comprising a relatively flat central portion and more angular edge portions adapted to be forced into engagement with a co-operating member when said connector portions are secured together.

2. The automobile buffer comprising a resilient buffer front formed of two spring steel strips having relatively adjustable co-operating connector portions and attacher connector portions, co-operating attacher members having connector portions adapted to co-operate with the corresponding connector portions of the buffer front, and connecting devices adjustably securing together said co-operating connector portions, some of said connector portions having a stiffening alining cross section comprising angular edge portions adapted to be forced into engagement with a co-operating member when said connector portions are secured together.

3. The automobile buffer comprising a resilient buffer front formed of two spring steel strips having relatively adjustable co-operating connector portions, and connecting devices adjustably securing together said co-operating connector portions, some of said connector portions having a similar stiffening alining cross section comprising angular edge portions adapted to be forced into engagement when said connector portions are secured together.

4. The automobile buffer comprising a resilient buffer front formed of spring steel strip having integral resilient end loops each

- 5 formed with an inturned connector portion substantially parallel to the adjacent front portion of the strip, coöperating spring strip attaching members having forwardly and outwardly curved portions and end connector portions adapted to coöperate with the corresponding connector portions of the buffer front, and connecting devices securing together said coöperating connector portions, said connector portions having an alining cross section comprising a relatively flat slightly curved central portion and more inclined angular edge portions adapted to be forced into engagement when said connector portions are secured together.

10 5. The automobile buffer comprising a resilient buffer front formed of spring steel strip having integral resilient end loops each formed with an inturned connector portion, coöperating spring strip attaching members having forwardly and outwardly curved portions and end connector portions adapted to coöperate with the corresponding connector portions of the buffer front, and connecting devices securing together said coöperating connector portions, said connector portions having an alining cross section comprising a relatively flat central portion and more inclined edge portions adapted to be forced into engagement when said connector portions are secured together.

15 6. The automobile buffer comprising a resilient buffer front formed of spring steel strip having integral resilient end loops each formed with an inturned connector portion, coöperating spring strip attaching members having end connector portions adapted to coöperate with the corresponding connector portions of the buffer front, and connecting devices securing together said coöperating connector portions, said connector portions having an alining cross section comprising inclined edge portions adapted to be forced into engagement when said connector portions are secured together.

20 7. The automobile buffer comprising resilient tempered spring steel strip members formed with overlapping connector portions adapted to be forced into engagement when said connector portions are secured together.

25 8. The automobile buffer comprising resilient members formed with overlapping connector portions having coöperating alining cross-sections comprising angularly bent alining edge portions and means to hold said connector portions together.

30 9. The automobile buffer comprising spring steel strip members each having a similar alining cross-section comprising a relatively flat central portion and an angularly bent alining edge portion and clamping means to hold together the connector portions of said members.

35 10. The automobile buffer including a resilient member having an alining cross-section comprising a bent alining edge portion and clamping means to hold together the connector portions of said members.

40 11. The automobile buffer comprising spring steel resilient strip members formed with coöperating overlapping connector portions having similar alining cross-section comprising an angularly bent alining edge portion and clamping means to hold said connector portions together.

45 12. The automobile buffer comprising resilient strip members and coöperating overlapping connector portions having similar alining cross-section comprising a bent alining edge portion and clamping means to hold said connector portions together.

50 13. The automobile buffer comprising resilient strip members and coöperating connector portions having alining cross-section comprising a bent alining edge portion and clamping means to hold said connector portions together.

55 14. The automobile buffer comprising a resilient steel strip member formed with a connector portion having a non-planiform alining cross-section and a bent edge and means to hold said connector portion in engagement with another coöperating buffer member.

60 15. The automobile buffer comprising a resilient steel strip member and a connector portion having a non-planiform alining cross-section and means to hold said connector portion in engagement with another coöperating buffer member.

65 16. The automobile buffer comprising resilient strip members each having a connector portion and clamping means to hold said connector portions together, at least one of said connector portions having an alining cross-section of non-uniform shape to promote alinement when said clamping means hold said connecting portions together.

70 17. The automobile buffer comprising a resilient strip member having a connector portion and a coöperating connector portion and clamping means to hold said connector portions together, said connector portions having coöperating alining cross-sections to promote their alinement when said clamping means hold them together.

75 18. The automobile buffer formed of spring steel strip having greater vertical width than thickness to render the same vertically rigid while more resiliently yielding in horizontal directions, said buffer comprising a transversely extending impact receiving member and end loops adapted to be located adjacent the automobile wheels, said

buffer comprising coöperating connector portions having alining cross-section and clamping means to hold said connector portions together while said alining cross-sections promote alinement thereof.

19. The automobile buffer formed of resilient strip and relatively rigid vertically while more resiliently yielding in horizontal directions, said buffer comprising a transversely extending impact receiving member and end portions adapted to be located adjacent the automobile wheels and attaching portions adapted to be attached to the automobile and located at adjustable distances apart to fit different width automobiles, said strips comprising connector portions formed

with coöperating alining cross-sections including a projecting portion and clamping means coöperating with said connector portions to force them together.

20. The automobile buffer formed of vertically rigid elements, said buffer comprising a transversely extending impact receiving member, connected attaching members and interposed end loops adapted to be located adjacent the automobile wheels, said buffer comprising coöperating connector portions having alining cross-section and clamping means to hold said connector portions together while said alining cross-sections promote the alinement thereof.

GEORGE ALBERT LYON.
